UNITED STATES PATENT OFFICE.

ALBERT WILSON, OF CHICAGO, ILLINOIS.

TYPE-COMPOSITION-BINDING FRAME.

Application filed March 4, 1926. Serial No. 92,278.

My present invention relates to type-composition binding frames, and my invention has for its main object to improve generally upon the type-composition frame illustrated and described in my application for Letters Patent of the United States, filed Dec. 19, 1925, Serial No. 76,354.

One of the main objects of my present invention is to provide a type-composition binding frame in which one of the walls is floatingly mounted and in which another of the walls is arranged to operate as lever means for pressing or forcing the type-composition to the floatingly attached lever, whereby more effectively to bind and maintain the page type-composition.

A further object of my invention is to provide a generally improved frame for use in the place of the pliable string ordinarily employed by printers in tying page type composition, and one in which the parts are so constructed and arranged as to enable the application and removal of the frame in much less time and with greater ease than the conventional string may be applied or removed.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a top plan view of my improved frame showing it as it appears when applied to page type-composition;

Fig. 2 represents an elevational view of a side wall included in the frame;

Fig. 3 represents an elevational view of the floating end wall included in the frame;

Fig. 4 is a detail sectional view taken substantially on the line 4—4 of Fig. 2;

Fig. 5 is another detail sectional view taken substantially on the line 5—5 of Fig. 3;

Fig. 6 is a top plan view showing the frame as it appears when collapsed;

Fig. 7 represents a top plan view showing the frame as it appears when separated from the page type-composition;

Fig. 8 is a detail sectional view showing the means by which to interlock the ends of the frame in type holding position, this view being taken on the line 8—8 of Fig. 7; and,

Fig. 9 is a fragmentary detail showing a

modified form of the floating hinge means.

My improved binding frame, in its preferred embodiment, comprises the side walls 10 and 11, and end walls 12 and 13. The side wall 10 has each of its extremities made in the form of opposing hinge knuckles 14 and 15. The opposing side wall 11 has one of its extremities made with like hinge knuckles 14 and 15, and has its opposite extremity made with a top hinge knuckle 16 in which is secured the top end of a locking pin 17 having a pointed end 18.

To the end wall 12 are secured as by means rivets 19 two floating members 20, each comprising a spring piece which extends from the rivets 19, where it is secured to the end piece, over a vertically-extending rib 21 formed on the end piece 12 to serve as a fulcrum. Each of the floating members 20 is outwardly offset or bent at 22 for a distance equal substantially to the elevation of the rib on which it reposes and terminates in a hinge knuckle 23 formed to fit between the top and bottom hinge knuckles 14 and 15 as clearly shown in the drawings. Suitable hinge pins 24, which are passed through the hinge knuckles 23 and the top and bottom hinge knuckles 14 and 15, connect the floating members 20 with their adjacent side walls. The end wall 12, thus floatingly hinged to the side walls 10 and 11, is of a length to fit between said side walls and to meet the same substantially at right angles.

The end wall 13 has its extremities 25 and 26 bent outwardly to fit respectively against the inner face of the side wall 10 and the inner face of the side wall 11 when the end piece 13 is closed to bind and maintain the page type-composition 27 as illustrated in Fig. 1. The outwardly bent extremity 25 terminates in a hinge knuckle 28 which fits between the top and bottom hinge knuckles 14 and 15 of the back wall 10 for receiving the hinge pin 29. The other extremity 26 terminates in a bottom hinge knuckle 30 for receiving the pointed locking pin 17 of the front wall 11 whereby, when the frame is placed about the page type-composition, to interengage the end wall 13 with the side wall 11. The end wall 13, during its closing movement, operates as a lever for forcing the component parts of the composition into a compact page. Obviously, the end wall 13, during its closing movement, forces the type-composition in the direction of the floating end wall 12 which yields as the com-

ponent parts of the composition are compacted. The provision of the floating end 12 also enables the insertion of suitable leads or other spacing devices from time to time, as occasion may require, in correcting the page type-composition.

The side walls 10 and 11 and the end walls 12 and 13 are each preferably made with outer longitudinal reenforcing ribs 31. The 10 end walls 12 and 13 are each provided with spaced lugs 32 by which suitably to withdraw the frame as an entity from the page type-composition through the employment of any suitable withdrawing apparatus of 15 the type set forth in my patent application above referred to.

In Fig. 9, I illustrate a modified form of floating hinge. In this form of construction the spring piece 33 is secured at its inner 20 end by means of rivets 34 to the end piece 12 as before and is bent outwardly at 35 to repose on a rib like fulcrum 36 as before, but this form of the spring piece extends entirely to the lower edge 37 of the end piece 25 12 and it has an extension 38 which extends behind the bottom hinge knuckle 15 of the adjacent side wall. The purpose of this arrangement is to reinforce the floating hinge connection between the end wall adjacent the 30 side wall and to prevent any turning or twisting of the spring piece 32 during the withdrawal of the frame from the page type-composition.

The utility of the foregoing binding 35 frame arises largely out of the provision of the floating end wall 12 and out of the relation thereto of the opposite end wall 13.

From the foregoing description, taken in connection with the accompanying drawings, it will be seen that an effective frame 40 has been disclosed for binding and retaining page type-composition, and one in which the floating end will enable the introduction of leads and in which the opposite end is capable of serving as a lever in quickly and 45 effectively forcing the component parts of the type-composition into a compacted page.

While I have illustrated and described the 50 preferred form of construction for carrying my invention into effect, this is capable of variation and modification without departing from the spirit of the invention. I, therefore, do not wish to be limited to the precise 55 details of construction set forth, but desire to avail myself of such variations and modifications as come within the scope of the appended claims.

Having described my invention, what I 60 claim as new and desire to secure by Letters Patent is:

1. A binding frame for type-composition including hinge connected walls for walling in the type-composition; the hinges for said 65 walls lying wholly outwardly beyond the

binding line formed by said walls; one of said hinges being formed to afford a floating resilient connection coacting with one of said walls to produce a type embracing enclosure, substantially as described. 70

2. A binding frame for type-composition including connected walls for walling in the type-composition; one of said walls being resiliently floatingly connected; and means for forcing the type-composition in the direction of said floatingly connected wall, 75 substantially as described.

3. A binding frame for type-composition comprising connected walls including as a feature an end wall floatingly connected 80 between side walls; and an opposing end wall arranged to be operated in the capacity of a lever to force the type-composition in the direction of said floatingly connected wall, substantially as described. 85

4. A binding frame for type-composition comprising side walls; an end wall floatingly connected between said side walls; and an opposing end wall hinged to one of the side walls and having means for interlocking with the other of the side walls, 90 substantially as described.

5. In a binding frame for type-composition, a pair of walls provided with hinge knuckles; a pair of opposed walls; floating hinge knuckles on one of said opposed walls 95 cooperating with the hinge knuckles of the pair of walls; and hinge pins connecting the hinge knuckles of the pair of walls with the hinge knuckles of one of the opposed walls, substantially as described. 100

6. A binding frame for type-composition including connected four walls adapted to embrace the type-composition and provided each on its outer side with a longitudinal 105 rib, one of said walls having hinge means adapted to co-act with and provide a floating connection with one of the other walls, substantially as described.

7. In a binding frame for type-composition, a pair of walls provided each with top and bottom hinge knuckles; a pair of opposed walls; floating members on one of the opposed walls provided with hinge knuckles fitting between said top and bottom hinge 110 knuckles; hinge pins connecting said top and bottom hinge knuckles and the interfitting hinge knuckles of the floating members; and extensions on said floating members underlying the bottom hinge knuckles, 115 substantially as described. 120

8. A binding frame for type composition including connected walls, adapted to embrace the type composition, one of the walls having a hinge connected to one of the other 125 of said walls, whereby a resilient, floating connection thereto is obtained substantially as described.

9. A binding frame for type composition including walls for embracing the composi- 130

tion, connections between said walls, and resilient means in said connections to permit one of the walls to be moved relatively to the other wall with which it is connected, substantially as described.

5 10. In a binding frame for type composition a pair of walls provided with hinge knuckles, a third wall, floating hinge knuckles on said third wall cooperating with

the hinge knuckles on the pair of walls, hinge pins connecting the hinge knuckles on the pair of walls with the hinge knuckles on the third wall, and means whereby the third wall may be tensioned against the floating hinge knuckles substantially as described.

15 In testimony whereof I have signed my name to this specification.

ALBERT WILSON.
